CLAIM

The ornamental design for an expandable pantry bin, as shown and described.

DESCRIPTION

FIG. 1 is a perspective view of an expandable pantry bin showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a cross-sectional view of the expandable pantry bin along line 8-8 of FIG. 7; and,

FIG. 9 is a cross-sectional view of the expandable pantry bin along line 9-9 of FIG. 7.

The broken lines showing lines labeled 8-8 and 9-9 in FIG. 7 depict cross sectional views shown in FIGS. 8-9 that form no part of the claimed design.
